UNITED STATES PATENT OFFICE.

HENRY ADICKS, OF DUTTONS LANDING, CALIFORNIA.

VAPORIZER FOR LIQUID FUELS.

1,345,822.

Specification of Letters Patent.

Patented July 6, 1920.

Application filed February 13, 1920. Serial No. 358,524.

To all whom it may concern:

Be it known that I, HENRY ADICKS, a citizen of the United States, residing at Duttons Landing, in the county of Solano, State 5 of California, have invented certain new and useful Improvements in Vaporizers for Liquid Fuels; and I do declare the following to be a full, clear, and exact description of the same, reference being had to the accompanying drawings, and to the characters of reference marked thereon, which form a part of this application.

This invention relates to means for gassing liquid fuels such as are used to run 15 internal combustion engines of various kinds.

The principal object of the invention is to provide a portable device by means of which a sufficient supply of fuel to start an 20 engine may be vaporized prior to its being drawn into the carbureter of the engine.

It is a well known fact by those who use them that tractors and the like are very hard to start in the winter and early spring, 25 when their owners' need for their service is the greatest. This is especially true since the majority of these machines burn distillate or kerosene, which at best are hard to vaporize.

In fact it has been my personal experience that in the majority of cases, in the seasons of the year mentioned, it will take sometimes as long as two hours to get a tractor or truck engine really going.

It is evident that under such conditions economy of operation of the farm etc. cannot be had, since not only is the work at a standstill, but the services and energies of at least one high priced mechanic are being 30 dissipated to no real purpose.

My device however does away with the above inconveniences and a tractor engine may be easily and quickly started with but very little exertion being necessary on the 45 part of the operator.

I have also provided a device which is not built into or permanently attached to the engine in any way, thereby preventing any changes being made to an equipment already installed.

A further object of the invention is to produce a simple and inexpensive device, and yet one which will be exceedingly effective for the purposes for which it is designed.

These objects I accomplish by means of such structure and relative arrangement of

parts as will fully appear by a perusal of the following specification and claims.

In the drawings similar characters of reference indicate corresponding parts in the several views.

Figure 1 is a vertical section through the device.

Fig. 2 is a cross section taken on a line 2—2 of Fig. 1.

Referring now more particularly to the characters of reference on the drawings, the numeral 1 denotes a tubular member substantially closed at its upper end except for a relatively small hole 2.

The lower end of the tube tapers somewhat as at 3 and is open at that end, to enable it to be inserted slightly into the mouth of the air intake of a carbureter. Should the style of carbureter demand, such lower 75 end of the tube may have a curved extension 4 so that the opening will be in a vertical instead of a horizontal plane.

Arranged in staggered and opposed order in the tube are a plurality of baffles or 80 cross partitions 5, each one joining at its lower end with the tube at an upward acute angle therewith to form a pocket 6 therebetween, being secured to the tube throughout its extent. Each baffle however 85 at its upper end terminates short of the wall of the tube to which it is adjacent, so that passageways 7 are had therebetween, the passageways being of course in staggered order as are the angled partitions 90 themselves.

A substantial lug 8 projects from one side of the tube, so that the same may be grasped by pliers when heated.

As shown in the drawings, it is my intention to form of the device a one-piece casting, of sufficient thickness of metal to withstand heat and retain the same for a certain length of time.

In operation, the tube is first laid horizontally in any suitable place, say on the ground, and some kerosene or distillate poured thereover, and the fuel then ignited. By the time the fuel has burned away, the tube will be sufficiently hot for the purpose, 100 that is, so that a damp finger held thereagainst will cause a sizzling sound.

The lug 8 on the tube is then grasped by a pliers or similar tool and the device held in a vertical position with its lower end 110 against the air intake of the carbureter of the engine to be started. At the same time

the nozzle of a squirt can is inserted into the hole 2 in the top of the tube, and left in an inverted position. This hole is so positioned that the liquid dropping from the 5 can will fall into the uppermost pocket 6. The metal being hot the liquid fuel will sizzle and boil, and a certain percentage, if not all, will rise as gas and then, owing to the suction of the engine, which is being turned 10 over at the same time, will be drawn through the passageway 7, from which point any fuel tending to condense will drop into the pocket thereunder, and will again boil and form gas, the process being repeated until 15 the bottom is reached, when the gasified fuel will be drawn into the carbureter.

When the engine is once started, the tube is withdrawn from its position, and may be placed in the tool box or hung up somewhere. With the aid of this device, the 20 starting of any engine, no matter how cold, is a matter of a few minutes, since the greatest hindrance to such starting in cold weather is the fact that the metal walls of the engine 25 being cold throughout, the fuel and especially the low and heavy grades now used, has no chance to vaporize, and merely enters the firing chambers of the cylinders as raw liquid, and hence will not ignite.

30 My device however provides fuel for the engine already vaporized, so that providing of course the ignition system and other parts of the engine are in good order, the latter will fire immediately.

From the foregoing description it will be 35 readily seen that I have produced such a device as substantially fulfills the object of the invention as set forth herein.

While this specification sets forth in detail the present and preferred construction of 40 the device still in practice such deviations from such detail may be resorted to as do not form a departure from the spirit of the invention, as defined by the appended claims.

Having thus described my invention what 45 I claim as new and useful and desire to secure by Letters Patent is:—

1. A vaporizer for liquid fuels comprising a vertical tube adapted to receive liquid fuel into its upper end and having its lower end 50 open and positioned adjacent the air intake of a carbureter, and pockets formed in the tube whereby the downward passage of the fuel will be retarded, the tube being thoroughly heated before being placed in position. 55

2. A vaporizer for liquid fuels comprising a vertical tube adapted to receive liquid fuel into its upper end and having its lower end open and positioned adjacent the air intake 60 of a carbureter, the tube being first thoroughly heated, and upwardly angled baffles arranged in staggered and opposed order in the tube, each baffle having a passageway at its upper end between the same and the 65 walls of the tube.

In testimony whereof I affix my signature.
HENRY ADICKS.
